US0D1038915S

(12) **United States Design Patent** (10) **Patent No.:** **US D1,038,915 S**
(45) **Date of Patent:** **** Aug. 13, 2024**

(54) **SPEAKER**

(71) Applicant: **Amazon Technologies, Inc.**, Seattle, WA (US)

(72) Inventors: **Michael Edward James Paterson**, Lafayette, CA (US); **Giles David Matthew McWilliam**, San Francisco, CA (US); **Marc Rene Walliser**, Viggiu (IT)

(73) Assignee: **Amazon Technologies, Inc.**, Seattle, WA (US)

(**) Term: **15 Years**

(21) Appl. No.: **29/911,825**

(22) Filed: **Sep. 8, 2023**

Related U.S. Application Data

(62) Division of application No. 29/803,102, filed on Aug. 10, 2021, now Pat. No. Des. 1,002,577, which is a division of application No. 29/650,422, filed on Jun. 6, 2018, now Pat. No. Des. 929,367.
